G. E. EVEY

CALF WEANER

Filed April 30, 1924

Fig. 1.

Inventor
George E. Evey.

By *George C. Adler*

Attorney

UNITED STATES PATENT OFFICE.

GEORGE E. EVEY, OF LISCO, NEBRASKA.

CALF WEANER.

Application filed April 30, 1924. Serial No. 710,090.

To all whom it may concern:

Be it known that I, GEORGE E. EVEY, a citizen of the United States, residing at Lisco, in the county of Garden, State of Nebraska, have invented certain new and useful Improvements in Calf Weaners; and I do hereby declare the following to be a full, clear, and exact description of the invention, such as will enable others skilled 5 in the art to which it appertains to make and use the same.

This invention relates to new and useful improvements in weaning devices, and particularly to devices for weaning calves.

15 In devices of this character, heretofore, difficulty has been experienced in the splitting of the wooden portion of the weaner, at the points where the hangers for the supplemental guard plate were driven into the 20 wood. Also, the calf was able to swing the main plate upwardly, and cause the supplemental guard plate to swing upwardly onto the main plate, and thus permit the calf to reach the teats of the cow. The 25 present invention includes novel features which seek to overcome these difficulties.

One object of the invention is to provide 30 means for obviating the driving of suspending devices through the wooden plate, which serves the additional functions of strengthening the plate, providing suspending means for the auxiliary guard plate, and also to provide means which will prevent the supplemental guard plate being swung upwardly onto the main plate.

Other objects and advantages will be apparent from the following description when taken in connection with the accompanying drawing.

40 In the drawing:

Figure 1 is a perspective view of a calf weaner made in accordance with the present invention, in the position assumed normally.

45 Figure 2 is a perspective view of the weaner in the position assumed when the calf attempts to move the guard plate onto the main guard.

Referring particularly to the accompanying drawing, 10 represents the main guard plate, which is preferably formed from wood of suitable thickness, and has the 50 elongated opening 11 therethrough, said opening extending through the upper portion of the plate, and resulting in the pas-

sage 12 for the nasal septum of an animal, with the inwardly opposing projections 13. Disposed in embracing relation around the end portions of the plate 10, and arranged across the smaller dimension thereof, are 55 metal bands 14, said bands being secured to the plate by means of rivets 15. The lower end of one side of each of the bands 14 is reduced in size and bent downwardly, below the lower edge of the plate 10, to form 60 the loop 16. The other end of the band is also reduced and slightly tapered, as shown at 17, such end extending downwardly and outwardly from the plate 10, at an angle, the terminal or tip of said end being provided with a spherical head. The auxiliary plate 18, is preferably a metal plate, and has the openings 19 in its upper edge portion which receive the said loops 16, whereby 65 the plate 18 is suspended for swinging 70 movement, below the main plate 10.

Should the animal succeed in causing the main plate 10 to swing upwardly, the auxiliary plate will assume a vertical depending position, in front of the mouth of the animal, thus effectively preventing reaching the teats 75 of the cow. The presence of the angular projections or ends 17, and the angle at which they extend, effectively prevent the plate 18 being swung upwardly onto the 80 plate 10. Should the plate 18 be caused to swing upwardly it will strike the projections 17 and fall again, by gravity into its normal depending position.

The projections 17 serve as prods against 85 the udder of the cow, when the calf attempts to reach the teats, but being provided with the spherical heads, these prods will not injure or cause pain to the cow. However, when these prods strike the udder, the cow will move away, thus frustrating the attempt of the calf.

The metal bands 14 serve three purposes, namely: As reinforcements for the wooden plate 10, to prevent splitting thereof; to provide the loops 16 on which the auxiliary guard plate 18 is suspended; and to provide the combined prods and stops for the plate 18.

While the guard plates 10 and 18 serve to effectively prevent the calf reaching the teats of the cow, they readily swing out of the way when the calf grazes.

While I have illustrated the tips of the projections 17 as formed with spherical 110

heads it will be understood that these may be simple blunt points.

Furthermore, the fact that the main plate 10 is formed from wood, insures against 5 soreness in the nose of the calf, which ordinarily occurs through frost, when this part of the device is made from metal.

What is claimed is:

1. A calf weaner including a main guard, 10 an auxiliary guard below the main guard, bands embracing the main guard and having means for suspending the auxiliary guard and limiting the movement thereof in one direction.
- 15 2. A calf weaner including a main guard, an auxiliary guard below the main guard, bands embracing the main guard, means on the bands for pivotally suspending the auxiliary guard, and means on the bands for

limiting the pivotal movement of the auxiliary guard in one direction.

3. A calf weaner including a main guard, an auxiliary guard below the main guard, bands embracing the end portions of the main guard and having their terminals 25 directed below the main guard, one of the terminals being formed into a loop and engaged in supporting relation to the auxiliary guard, and the other terminal being directed at an angle from the band for engagement by the auxiliary guard to limit the movement thereof in one direction.

In testimony whereof, I affix my signature, in the presence of two witnesses.

GEORGE E. EVEY.

Witnesses:

G. W. SAMPON,
REUBEN LORISCO.
